UNITED STATES PATENT OFFICE.

HENRY J. VAN HAAGEN, OF NEW YORK, N. Y.

ADVERTISING-SIGN.

SPECIFICATION forming part of Letters Patent No. 788,967, dated May 2, 1905.

Application filed May 3, 1897. Serial No. 634,833.

To all whom it may concern:

Be it known that I, HENRY J. VAN HAAGEN, a citizen of the United States, residing at New York, county and State of New York, have 5 invented certain new and useful Improvements in Advertising-Signs, fully described and represented in the following specification and the accompanying drawings, forming a part of the same.

10 My invention relates to advertising-signs, and has for its object the utilization to the utmost of available space for advertising purposes.

At the present time desirable advertising-space, especially in crowded cities, is found insufficient for the demands of advertising, and I propose by the use of my invention to practically multiply the available advertising-space. I propose to accomplish this by an 15 arrangement which shall present at the same point of view a succession of different advertisements at successive short intervals of time. Each advertisement will be displayed long enough to permit its inspection by 20 observers, when it will be replaced by another advertisement, which in turn will be after a brief interval replaced by another and in due course by the one first displayed. Thus each advertisement will be presented with sufficient 25 frequency for the observation of practically all persons who would see the same if it were continuously displayed. Moreover, the successive appearance and disappearance of the advertisement will attract attention, 30 so that the advertisement will be much more effective for that reason than if it remained continuously in position.

My invention may also be employed for displaying other things than advertisements—as, 35 for instance, pictures or ornamental decoration or scenery on the stage.

I secure the results above mentioned by forming the advertising-space of the surfaces of a number of prismatic rods. One surface 40 is made up of one face of each of the rods. This surface presents one advertisement or picture, the surface of each rod corresponding to that advertisement having upon it a section of the advertisement. A second face of

each of the rods make up together a second 50 advertising-space. A third surface of each of the rods make up a third advertising-space, and so on. Three faces for each of the rods is a convenient number of faces, but I do not confine myself to that number. I cause the 55 rods to move in unison for the purpose of presenting at intervals different faces by means of proper mechanism. I do not limit myself to any particular form of mechanism. One form which I find it convenient to employ 60 consists of a spring which is connected by gearing or otherwise with each of the rods and gives the latter a tendency to rotate. Their rotation is, however, restrained by the contact of a catch with a stop. The catch is 65 intermittently withdrawn by means of clock-work at short intervals, permitting the rotation of the rods under tension of the spring.

My invention also consists in details of construction which are shown in the drawings 70 and referred to in the specification and which will be pointed out in the claims.

In the drawings, Figure 1 represents a face view of my mechanism, showing the rods forming by the conjunction of their faces the advertising-space. Fig. 2 is a sectional view through the inclosing case and operating mechanism on the line 2 2 of Fig. 1. Fig. 3 is a section on the line 3 3 of Fig. 1. Fig. 4 is a rear view with the back of the case removed. Fig. 5 is a front view of the actuating mechanism. Fig. 6 is an end view of the same, taken from the left of Fig. 5. Fig. 7 is a sectional view on the line 7 7 of Fig. 5. Figs. 8 and 9 show a modification. 85

The rods A have at each end a pivotal projection, which rotates freely in corresponding holes in the strips B B'. The pivotal projections C from one end of the rods are bent to form a crank and pass through holes in a connecting-rod D. This connecting-rod is given a movement of revolution by the crank-shaft E, which carries on one end a miter gear-wheel F, engaging with another miter-gear F' on the shaft G. The shaft G is driven by intermitting gears from a spring under tension H. On the shaft G is mounted a disk I, which carries mounted within it at intervals several 90 95

spring-catches J, which have a movement radially to the wheel and are pressed outward by the springs J'. They are guided in their movement by transverse pins j, which pass 5 through radial slots in the disk I and project on one side therefrom, as shown. A stop K is provided in the path of the catches J and of a shape adapted to receive the same and so placed that the catches J will escape it when 10 they are retracted. The contact of the catches J with the stop K checks the rotation of the crank-shaft under stress of the spring H. These catches are intermittently pressed backward toward the center of the disk I by means 15 of a pivoted lever L, operated by the clock-work shown in the right-hand part of Fig. 5. This clockwork is continuously in rotation and moves a toothed wheel M, into which the tail L' of the lever L is pressed by the spring 20 N. The other end of the lever L has a position just outside of the path of the pins j when the tail of the lever is resting in one of the notches in the wheel M.

The outer end of the lever L is provided 25 with a pivoted portion L², held in the position shown by a spring L³. This pivoted piece L² is, as is shown in plan view, Fig. 9, free to move inward against the spring L³. This construction is not essential to the operation 30 of the device, but is desirable for this reason: If the teeth of the wheel M be not cut with perfect exactness, it may happen that the disk I may be released before the tail L' reaches the highest point to which it is pressed by a tooth. In that case the next pin j will strike 35 against the forward end of the lever L. The spring L³ then permits the part L² to yield, when the tail L' drops into the succeeding notch, and thereupon the pivoted piece L² 40 falls into position beneath the pin j, as shown in Figs. 5 and 8. Assuming the position of the mechanism to be that shown in Fig. 5, the rotation of the wheel M will gradually push out the tail L' of the lever L, at the same 45 time raising it to press back one of the spring-seated catches J. When the wheel M is moved far enough to cause L' to rest upon the point of one of its teeth, the front end of the lever L will be lifted sufficiently to move 50 the catch J above the stop K. The disk I will now be free to rotate under the stress of the spring H and will give rotation through the miter gear-wheels F F' to the crank-shaft E and the rods A. As soon as the tail of the 55 lever L is past the tooth which has pushed it out it drops into the next recess and the front end of the lever L is depressed. The movement of the disk I continues until the next catch J strikes the stop K, when its 60 movement is arrested, and it is held in such position until the tail L' of the lever L is again pushed out by the next tooth of the wheel M, when the operation is repeated. At 65 each release of the disk I and its rotation for the space between two of the catches J the

rods A will be caused to simultaneously move, through the operation of the crank-shaft E and the connecting-rod D, so as to present simultaneously a new face. Preferably the revolution of the wheel M is so timed that release of the disk I will occur at intervals of about a minute, so that a change will be made in the advertisement displayed by the mechanism at like intervals. 70

Other means than those above described 75 may be used for rotating the rods without departing from my invention. Thus, for instance, electrical apparatus might be employed for this purpose.

In Figs. 8 and 9 is shown a modified form 80 of the device for tripping the lever L, which is adapted according to adjustment to give different rates of movement to the rods. This device consists of several sleeves P Q R, held by set-screws to a vertical shaft S, which gears 85 with the clockwork. These sleeves are each provided on their lower face with teeth, as shown, which engage with the tail L'. As shown, the sleeve P has two teeth, the sleeve Q four teeth, and the sleeve R eight teeth. 90 The tail L' is caused to engage the sleeve on a radial line parallel with the axis of the lever in order that the distance between the pivotal point and the bearing-point of the tail L' may be the same whichever one of the sleeves is 95 engaged. The interval of movement of the rods will be determined by the fact as to whether one or the other of the sleeves P Q R are in the depressed position.

Other forms of the tooth-carrying mechanism for operating the lever L, as well as other forms of the various other parts of the apparatus besides those shown, may be used without departing from my invention. 100

What I claim is— 105

1. The combination of a series of rods placed side by side said rods having two or more faces and the corresponding faces of the several rods being provided each with a section of an advertisement or other legend or picture where- 110 by when all of the faces are presented together a complete advertisement or picture will be displayed, mechanism placing the rod under tension to move, spring-catches for arresting the rod, a trip-lever for operating the catches 115 and clock mechanism for operating the trip-lever, substantially as set forth.

2. The combination of a rotary member, means tending to rotate said member, a stop, a series of spring-pressed catches carried by 120 the rotary member for engaging the stop to arrest the rotation of said member, a trip-lever L, means for operating said lever at intervals, and a spring-pressed yielding piece L² carried by said lever for engaging said catches, 125 substantially as set forth.

3. The combination of a series of rods placed side by side said rods having two or more faces and the corresponding faces of the several rods being provided each with a section of an ad- 130

vertisement or other legend or picture whereby when all of the faces are presented together a complete advertisement or picture will be displayed, a spring placing the rods under tension to move, catches for arresting the rods, a trip-lever L for operating the catches and clock mechanism giving movement to a series of adjustable notched faces one or the other of which may be adjusted in position as desired

for operating the trip-lever, substantially as set forth.

In testimony whereof I have hereunto set my hand in the presence of the two subscribing witnesses.

HENRY J. VAN HAAGEN.
